SOLENOID CONTACTOR

Marvin G. Nelsen, Skokie, Ill., assignor to Guardian Electric Manufacturing Co., Chicago, Ill., a corporation of Illinois

Application April 16, 1942, Serial No. 439,226

5 Claims. (Cl. 200—111)

The present invention relates to electro-magnetic devices, and more particularly to solenoid contactors of the type wherein energization of the solenoid controls the make or break of cooperating contact members connected in an electrical circuit.

It is well known that in solenoid construction it is highly desirable to employ a ferrous metal plug within the coil, in a position to serve as a stop for limiting the movement of the plunger of the solenoid in one direction, and which also serves to increase the magnetic efficiency of the assembly and permits a reduction in the effective length of the plunger so that the moving parts of the assembly may be of reduced weight and thereby insure easier and smoother operation of the device, while at the same time reducing vibration incident to operation of the solenoid.

A common practice in solenoid construction consists in utilizing a ferrous metal plug, mounted in fixed relation within the coil of the solenoid. In some instances provision has been made for adjusting the plug with respect to the coil for varying the stroke or range of movement of the plunger in one direction by the use of shims or washers associated with the anchorage structure of the plug within the coil of the solenoid. The addition or removal of shims or washers is practiced by the "cut and try" method and which, while obtaining a fair degree of adjustment, does not permit obtaining the nicety of adjustment that is frequently desired and is necessary in connection with solenoids designed for exact or predetermined ranges of movement of the plungers, or where the device is designed to exact specifications for use in connection with a predetermined electrical current. Moreover, such practice has been found to be time consuming and expensive and does not conveniently lend itself to conveniently make such adjustments of the plug of the solenoids in the "field."

One of the objects of this invention resides in the provision of novel means which is constructed and arranged for ease in assembly and by virtue of which construction it is possible to quickly and easily obtain a nicety of adjustment of the plug so as to obtain a relatively exact predetermined range of movement of the plunger, or by virtue of which the plunger may be properly and efficiently actuated by energizing of the coil by exact electrical current characteristics.

A further object resides in the provision of a novel construction of a unitary solenoid contactor device wherein the contact elements are fully enclosed at all times.

Still another object of this invention is to provide an improved form of unitary solenoid contactor which is relatively simple in construction, capable of quick and easy assembly, durable in operation and which is capable of economical manufacture.

Other objects and advantages of this invention will be apparent from the following description, taken in connection with the accompanying drawing in which—

Figure 1 is a plan elevation of my novel solenoid contactor device, embodying the present invention, with parts broken away to show details of construction.

Figure 2 is a front end view of the assembly.

Figure 3 is a rear view of the assembly.

In the construction illustrated in the drawing, the solenoid contactor device is a unitary assembly and includes a mounting bracket provided with a base member 10 adapted to be secured to a suitable mounting and an upright mounting member 11. As may be seen in the drawing, the entire assembly is carried by the mounting bracket and includes a solenoid 12 comprising a cup-shaped housing 14, the closed end of which is rigidly secured to one face of the upright member 11, such as by spot welding. Mounted within the housing is an annular coil 15 surrounding a tube 16 which serves as a guide for a reciprocably movable plunger indicated at 17. The open end of the housing of the solenoid is closed by an end plate or disc 18 as seen in Figure 1 of the drawing, and for convenience in assembling, the outer open end of the housing is interiorly shouldered to receive the disc 18 and the extreme free edge of the housing is rolled over against the disc 18 so as to permanently enclose the coil 15.

As may be seen in the drawing, the tube 16 is flared at one end, as indicated at 16a to abut against the outer end of the coil and the opposite end of the tube extends through aligned apertures in the closed end of the cup-shaped housing 14 and the upright member 11, and is flared outwardly as indicated at 16b against the outer surface of the member 11, to firmly anchor the coil in position within the housing 14, and to permit movement of the plunger with the guide tube 16.

Mounted in the outer end of the tube 16 of the solenoid is a ferrous metal plug 22, the forward end of which is formed with a frusto-conical recess, as indicated at 22a, corresponding generally to the cooperating, tapered, frusto-conical end 17a of the plunger 17. The other end of the plug is formed with a shank 23 which

is externally threaded for threaded engagement in an aperture formed in the adjacent housing end wall or disc 18. As shown in the drawing, the shank 23 is of reduced size, but if desired may be of the same size as the plug proper, so as to obtain increased power for operating upon the plunger. The outer end of the shank 23 which projects exteriorly of the end wall 18 is formed with a slot 24 to accommodate a screw-driver or other suitable implement by virtue of which the plug may be quickly and easily rotated so as to move it toward or away from the adjacent end of the tube 16 and thereby vary its relationship to the cooperating end of the plunger 17. Mounted on the threaded outer end of the shank 23 is a lock-nut 25 adapted to abut against the outer surface of the housing end disc 18 so as to firmly and fixedly lock the plug 22 in a desired position of adjustment.

It is by virtue of this construction that it is possible to quickly and easily shift the plug 22 axially within the tube 16 so as to obtain maximum efficiency in operation of the assembly. Such an arrangement also permits accommodation for variations in manufacture and assembly of other elements, which may have a bearing on the effective operating range of movement of the plunger. In certain devices of this general character, it is highly desirable to obtain a relatively exact range of movement of the plunger and when such range of movement must be maintained, it will be apparent that there may be variations in the fabrication of other elements associated with the operation end of the plunger, as well as variations in overall dimensions of the assembly of said other elements. Hence, it is possible to readily accommodate such variations by providing a nicety of adjustment of the plug 22 with respect to the adjacent end of the plunger 17 in order to obtain the exact specified range of movement of the plunger 17. It will also be apparent that in certain instances where a solenoid is constructed to certain specifications for operation by a definite electrical current, it is possible that a variation of voltage will impair the efficient operation of the plunger of the solenoid. It is, therefore, possible to overcome this condition by the construction described, in order to obtain a nicety of adjustment of the cooperating plug 22 relatively to the cooperating end of the plunger.

Mounted on the upright member 11 of the mounting bracket are a plurality of spaced apart studs 30 which extend horizontally in a direction opposite to the solenoid housing 14. Mounted on said studs in abutting relation to the upright member 11, is a panel 32 of insulating material on the outer face of which is mounted, at opposite sides of the axis of the solenoid, a pair of contact members 33, 34, including contact buttons 33a and 34a. The outer ends of the contact members 33 and 34 are provided with suitable terminals 35 and 36, respectively, adapted to be connected in an electrical circuit to be controlled. Mounted on the outer end of the plunger is a contact bar 38 positioned against a fixed stop or abutment shoulder 39 on the plunger. Said bar is of elongated form and is provided with a pair of contact buttons 40 and 41 disposed in alignment with the cooperating contact buttons 33a and 34a, respectively. Surrounding the plunger 17 is a coil spring 43, extending through an aperture 32a formed in the insulating panel 32, and abutting at one end against the upright member 11 and at its opposite end against the underside

of the contact bar 38. Mounted on the extreme outer end of the plunger is a coil spring 44, adapted to react at one end against the top of the contact bar 38 and at its opposite end against a fixed collar 45 on the outer end of the plunger. It will be apparent that the coil spring 43 normally serves to oppose movement of the plunger and contact bar 38 and tends to urge the plunger to its extended position as seen in Figure 1 of the drawing. The construction is such that when the solenoid is energized a yielding pressure is imparted to the contact bar 38 by compression of the coil spring 44 and by virtue of which movement the contact bar compresses the coil spring 43 until contact buttons 40 and 41 engage contact buttons 33a and 34a. This arrangement of coil springs, which is well-known, is such that when the solenoid is de-energized, the coil spring 44 is first relieved of its tension so that the fixed abutment shoulder 39 of the plunger imparts "a hammer blow" to the contact bar 38 to initiate its outward movement and effect immediate separation of the respective pairs of contact buttons, and thus tends to reduce the tendency to arcing. The two sets of contact buttons, as well as the outer ends of the plunger and its spring assembly, are fully enclosed by a cap 46 of insulating material. This cap is mounted on the outer ends of the studs 30, and is held with the panel 32 firmly against the upright member 11 by nuts 30a. As may be seen in the drawing, this cap is formed with a recess 47 for accommodating the outer ends of the contact bar 38 and serving to guide the latter in its movement toward and away from the contact buttons 33a and 34a. The base of said recess, as indicated at 48, serves to limit the outward movement of the contact bar under pressure of the coil spring 43, and this in turn limits the outward movement of the plunger 17. The sides of the cap 46 are notched as indicated at 49, to permit straddling of the contact members 33 and 34.

The novel construction of the unitary solenoid contactor above described lends itself to economical manufacture and assembly. By virtue of such construction, it is possible to fabricate the device as three main assemblies, namely, the mounting bracket and the solenoid field, the insulating panel carrying the contact buttons, and the plunger with its associated springs and contact bar, thus enabling the parts to be quickly and easily assembled and which assembly is completed by the placement of the cap 46 in position on the studs.

Although I have herein shown and described one preferred embodiment of my invention, manifestly it is capable of modification and rearrangement of parts without departing from the spirit and scope thereof. I do not, therefore, wish to be understood as limiting this invention to the precise form herein disclosed, except as it may be so limited in the appended claims.

I claim as my invention:

1. For use with a mounting bracket including a base member and an upright member, a solenoid adapted to be supported on said upright member and comprising a cup-shaped housing having the closed end thereof rigidly secured to the upright member, an annular coil mounted within the housing, a tube mounted in said coil and having one end flared against the outer end of the coil and its opposite end extending through an opening in the closed end of the cup-shaped housing and adapted to extend through an aligned opening in said upright

member and flared against the outer surface of said upright member to fixedly secure the coil in the housing, a ferrous metal plunger reciprocably mounted in one end of said tube and having its outer end projecting through said aligned openings, an end plate secured in the open end of said cup-shaped housing, and a ferrous metal plug fixedly connected to said plate and extending into the opposite end of the coil.

2. In a device of the character described, the combination of a mounting bracket including a base member and an upright member, a solenoid supported on the upright member and comprising a cup-shaped housing having the closed end thereof rigidly secured to said upright member, an annular coil mounted within the housing, a plunger reciprocably mounted in the coil and having its outer end projecting through aligned openings in said upright member and said closed end of the housing, a plurality of spaced apart studs projecting horizontally from the upright member at the side opposite said housing, a panel of insulating material mounted on the studs adjacent the upright member, a pair of spaced contact buttons on the outer face of the panel, a contact bar mounted on the outer end of and disposed against a fixed abutment on the plunger, said bar including a pair of contact buttons aligned for cooperative engagement with the contact buttons on the panel, a coil spring on the plunger between the contact bar and upright member and serving to yieldingly urge the plunger to extended position together with the contact bar and its contact buttons out of engagement with the contact buttons on the panel, and a cap of insulating material mounted on the outer portion of said studs and enclosing the outer end of the plunger, the contact bar and the contact buttons on the panel.

3. In a device of the character described, the combination of a mounting bracket including a base member and an upright member, a solenoid supported on the upright member and comprising a cup-shaped housing having the closed end thereof rigidly secured to said upright member, an annular coil mounted within the housing, a plunger reciprocably mounted in the coil and having its outer end projecting through aligned openings in said upright member and said closed end of the housing, a plurality of spaced apart studs projecting horizontally from the upright member at the side opposite said housing, a panel of insulating material mounted on the studs adjacent the upright member, a pair of spaced contact buttons on the outer face of the panel, a contact bar mounted on the outer end of and disposed against a fixed abutment on the plunger, said bar including a pair of contact buttons aligned for cooperative engagement with the contact buttons on the panel, a coil spring on the plunger between the contact bar and upright member and serving to yieldingly urge the plunger to extended position together with the contact bar and its contact buttons out of engagement with the contact buttons on the panel, and a cap of insulating material mounted on the outer portion of said studs and enclosing the outer end of the plunger, the contact bar and the contact buttons on the panel, said cap

being formed with guideways for guiding the bar during its reciprocable movement and insuring alignment of its contact buttons with the contact buttons on said panel.

4. In a device of the character described, the combination of a mounting bracket including a base member and an upright member, a solenoid supported on the upright member and comprising a cup-shaped housing having the closed end thereof rigidly secured to said upright member, an annular coil mounted within the housing, a plunger reciprocably mounted in the coil and having its outer end projecting through aligned openings in said upright member and said closed end of the housing, a panel of insulating material mounted on the upright member, a pair of spaced contact buttons on the outer face of the panel, a contact bar mounted on the outer end portion of and disposed with the face adjacent said panel against a fixed abutment on the plunger, said bar including a pair of contact buttons positioned for cooperative engagement with the contact buttons on the panel, a coil spring on the plunger between the contact bar and upright member and serving to yieldingly urge the plunger to extended position with the contact bar and its contact buttons out of engagement with the contact buttons on the panel, a coil spring on the outer end of the plunger engaging the opposite face of said contact bar for yieldingly urging the latter against the fixed abutment, and a cap of insulating material mounted on the panel and enclosing the outer end of the plunger, the contact bar and the contact buttons on the panel.

5. In a device of the character described, the combination of a mounting bracket including a base member and an upright member, a solenoid supported on the upright member and comprising a cup-shaped housing having the closed end thereof rigidly secured to said upright member, an annular coil mounted within the housing, a plunger reciprocably mounted in the coil and having its outer end projecting through aligned openings in said upright member and said closed end of the housing, a panel of insulating material mounted on the upright member, a pair of spaced contact buttons on the outer face of the panel, an elongated contact bar loosely mounted on the outer end portion of and disposed with the face adjacent said panel against a fixed abutment on the plunger, said bar including a pair of contact buttons positioned for cooperative engagement with the contact buttons on the panel, a coil spring on the plunger between the contact bar and upright member and serving to yieldingly urge the plunger to extended position with the contact bar and its contact buttons out of engagement with the contact buttons on the panel, a coil spring on the outer end of the plunger engaging the opposite face of said contact bar for yieldingly urging the latter against the fixed abutment, and a cap of insulating material mounted on the panel and enclosing the outer end of the plunger, the contact bar and the contact buttons on the panel, said cap being formed with guideways for guiding the bar during its reciprocable movement for insuring alignment of its contact buttons with the contact buttons on the panel.

MARVIN G. NELSEN.
